CLAIM

The ornamental design for a tape dispenser, as shown and described.

DESCRIPTION

FIG. 1 is a perspective view of a tape dispenser showing my new design;

FIG. 2 is a front view of the tape dispenser shown in FIG. 1;

FIG. 3 is a top view of the tape dispenser shown in FIG. 1; FIG. 4 is a bottom view of the tape dispenser shown in FIG. 1;

FIG. 5 is a left side view of the tape dispenser shown in FIG. 1;

FIG. 6 is a right side view of the tape dispenser shown in FIG. 1;

FIG. 7 is another perspective view of the tape dispenser shown in FIG. 1;

FIG. 8 another front view of the tape dispenser shown in FIG. 1;

FIG. 9 is another top view of the tape dispenser shown in FIG. 1;

FIG. 10 is another bottom view of the tape dispenser shown in FIG. 1;

FIG. 11 is another left side view of the tape dispenser shown in FIG. 1; and,

FIG. 12 is another right side view of the tape dispenser shown in FIG. 1.

The broken lines in the drawings showing a roll of tape are included to show an article in the environment that forms no part of the claimed design.

1 Claim, 9 Drawing Sheets
